UNITED STATES PATENT OFFICE

FRANK A. MILLIFF AND JOHN A. MILLIFF, OF LOS ANGELES, CALIFORNIA

PETROLEUM REFINING APPARATUS

Application filed January 11, 1926, Serial No. 80,583. Renewed December 27, 1928.

Our invention relates to petroleum refining apparatus and includes a novel form of fractionating tower.

In one of the more modern methods of refining petroleum oil, the crude oil is heated in a pipe still up to about 500° F. The hot crude oil is then conducted from the still to a vaporizer in which the more volatile hydrocarbons are separated from the residuum as vapors. The mixture of these vapors so separated is then conducted through a dephlegmator which cools the vapor mixture to a point where a certain group of the less volatile hydrocarbon vapors condense and are removed from the vapor mixture. The remainder of the vapor mixture goes to a second dephlegmator, where it is further cooled, and another group of the remaining hydrocarbon vapors are condensed and removed from the mixture. In the same manner the remainder of the vapor mixture is progressively cooled and condensed in further dephlegmators. In the present practice a total of six dephlegmators is generally used, the vapor mixture which leaves the last dephlegmator being completely condensed in a condenser. Each of the groups of hydrocarbons which a series of dephlegmators thus separates out from the vapor mixture may comprise a commercial product, or it may be further refined. In order of their boiling points, and, hence, in the order in which they are condensed from the vapor mixture, these products are commonly termed gas oil, stove oil, several grades of distillate, kerosene and gasoline.

Inasmuch as the same refinery may find it necessary to purchase crude petroleum composed of various proportions of hydrocarbons, it is very desirable that in a refining process such as just described, complete control of the temperatures of condensation may be possible in each stage of reduction of the vapor mixture into liquid hydrocarbon products. It is also desirable to effect an economy in first cost of construction and in the cost of operation of such a fractional distillation apparatus.

It is an object of our invention, therefore, to provide a single fractionating tower which

takes the place of the several dephlegmators and accomplishes a separation of the several hydrocarbon products enumerated above from a mixture of their vapors.

It is also an object of our invention to provide in such a fractionating tower a series of vapor condensing sections, the temperature of each of which is controllable so that as the vapor mixture passes through it a predetermined group of hydrocarbons is condensed therein.

It is another object of our invention to provide in such a fractionating tower a re-boiler associated with each vapor condensing section in which the condensate from that section is re-boiled to drive off any hydrocarbons condensed in that section which are more volatile than those desired in the product to be removed therein.

It is a still further object of our invention to provide in said vapor condensing sections novel condensate pans having vaporizer passageways therein and caps for downwardly deflecting the vapor rising through these passageways, so that when condensate stands at a certain level in said pans the vapor will be forced to bubble through the condensate in order to escape upwardly.

Another object of our invention is to provide means for equally distributing the vapor through the condensate along the whole length of these caps on each side thereof.

Still another object is to provide means for determining the level of condensate in each pan, and hence the depth below the surface of the condensate at which the vapor is released.

A further object of our invention is to provide means for conducting the overflow of condensate from each pan to the one next below it and a novel and efficient means of introducing a liquid hydrocarbon reflux into the condensate so that it will be thoroughly mixed therewith as it enters the lower pan.

Another object is to provide the re-boilers with heat exchange elements which are supplied through piping with a heating medium, such as hot residuum, in such a manner that these heat exchangers may communicate in parallel fashion between the hot residuum

supply and cool residuum return lines; or else they may be connected together so that all the residuum passes into the lower heat exchanger and from it to the one next above it, and so on up in series to the uppermost heat exchanger which has outlet connection with the cool residuum return lines.

Yet another object of our invention is to provide a novel condensate tap from each re-boiler whereby the condensate is drawn from a lower level of the re-boiler and yet whereby the surface of the condensate is maintained at a predetermined level in the re-boiler.

It is a further object to provide a re-boiler for each condensing section in which the condensate from that section may be treated by means for applying dry heat thereto or by means for releasing steam therein.

Another object of our invention is to provide means for cooling all of the re-boilers when a drop in temperature becomes necessary.

Other objects and advantages of our invention will be made apparent in the following specification and in the accompanying drawings, in which

Fig. 1 is a diagrammatic view showing our fractionating tower employed in a typical apparatus for refining petroleum.

Fig. 15 is a vertical sectional view of a novel gas pocket preventer which is a part of our invention.

Referring to the drawings in detail, the apparatus for refining petroleum shown in Fig. 1 is a continuous pipe still process. This process has a pressure pump 10 which draws crude petroleum from the crude storage tank 11 and pumps it through a pipe 12 to the primary heat exchangers 13 from which it returns through a pipe 14 to the secondary heat exchangers 15, from which it is led by a pipe 16 to a water separator 17, from which a pipe 18 conducts the crude oil to the pipe still 25. A gas or oil burner 26 provides fire to heat the still pipes 28, through which the crude oil circulates and from which the oil is conducted through a pipe 30 at a temperature of about 500° F., when treating a certain grade of oil chosen as an example, to a vaporizer 31. In the vaporizer 31 the hydrocarbons with boiling points below 500° F. separate out from the residuum in the form of vapors. The residuum is still very hot and is conducted from the bottom of the vaporizer 31 through the pipe 32 to the secondary heat exchangers 15, where it heats the charging crude and is cooled thereby, then passing on through a pipe 33 to a pipe 34 which leads to a residuum storage (not shown).

The mixture of vapors separated from the residuum, which are condensable at different temperatures, pass from the vaporizer 31 through a vapor line 35 to a centrifuge 36. In this centrifuge entrained particles of liquid are removed from the vapor in the manner to be described later, and are returned to the vaporizer 31 through a pipe 37. The vapor passes from the centrifuge 36 through a vapor line 38 which connects with a lower fractionating unit 40 of the fractionating tower generally designated as 41.

The fractionating tower 41 in the embodiment shown has a vertical shell formed by stacking a number of shell sections of the same cross section one upon the other. These shell sections are of two kinds, viz. condenser sections and re-boiler sections, each of the former having one of the latter disposed immediately beneath it and in communication therewith to form a fractionating unit. Stacked upon the bottom fractionating unit 40 and extending vertically upward therefrom are fractionating units 52, 53, 54, 55, 56 and 57, all of which are identical in construction.

The bottom fractionating unit 40, as illustrated in Figs. 2, 3 and 4, is composed of a vapor vestibule condensing section 60 and a tower base re-boiler section 61.

The section 60 has a shell 62 of rectangular horizontal section, which is open at the upper

and lower ends where attaching flanges 65 and 66 respectively are formed upon the shell 62. A vapor inlet opening 67 is formed in the medial portion of a wall 68 of the shell 62 and the lower end of the vapor line 38 is secured against the wall 68 by a flange 69 so that the vapor line 38 communicates through the hole 67 with a vestibule chamber 70 provided in the middle portion of the section 60. Fitted into the shell 62 just above the chamber 70 and welded to the shell is a vapor distributor plate 72. This plate is provided with vapor distributing holes 73 of an aggregate cross section equal to that of the vapor inlet opening 67, and uniformly distributed over the surface of the plate 72.

A condensing pan 75 has a floor plate 76 which is formed to fit the inside of the shell 62 and is welded therein in horizontal position medially between the distributor plate 72 and the upper end of the section 60.

Referring to Figs. 4, 5, 8 and 9 for a detailed description of the pan 75, six parallel vapor riser openings 77 are formed in the pan floor 76 and have walls 78 rising upwardly along their edges to a uniform height.

A cap 80 rests down over each riser opening 77 outside the walls 78 upon the floor 76. Each cap 80 has a ceiling 81, side plates 82 bent downwardly therefrom, and end plates 83 closing the end openings. A cavity 84 is thus formed in the cap 80 which opens at the lower edge of the side and end walls 82 and 83. Spacing studs 90 formed on the outside of the walls 78 space the cap 80 a distance from these walls. Notches 91 are formed in the lower edges of cap side and end walls 82 and 83, the apexes of which are all on a given level. An angle iron 92 is welded to the outer face of cap walls 82 and 83 so as to provide a horizontal shelf 93 projecting outwardly from the walls 82 and 83 with its lower face upon the level of the apexes of the notches 91.

As will be seen in the plan view of Fig. 5, the condensing pan 75 is provided with an inlet or condensate discharge pipe 94 and an outlet or condensate collector pipe 95 which are projected through holes formed in the walls of the shell 62 and welded to these walls so that these two pipes are disposed parallel to and a small distance from the floor 76 at opposite ends of the parallel riser opening caps 80. Holes 96 are formed along the bottom of the pipe 95 to allow liquid to pass therein from the pan 75.

Referring to Figs. 6, 7 and 9, the inlet and outlet pipes 94 and 95 project outwardly at one end beyond the wall of the shell 62 and are threaded to receive a cap 97 and a joint flange 98 respectively. Attached to the flange 98 is an adjustable weir 99 having a housing 100 and a rotor 101 having a weir opening 102 formed therein. The rotor 101 is rotatably seated in the housing 100 so that

liquid may flow through the valve 99 only by passing through the weir opening 102. The rotor 101 may be rotated manually to control the elevation of the weir opening 102 and, hence, the level which the liquid must attain in the pipe 95 before it will flow through the opening 102 by gravity. The novel features of this adjustable weir are fully shown, described and claimed in our United States Letters Patent issued March 8, 1927, No. 1,620,164, and reference may be had to that patent for further information thereon.

The other end of the outlet pipe 95 is closed by a welded head 105, as shown in Figs. 6 and 9, and the other end of the inlet pipe 94 is closed by a welded head 106. Disposed through a hole in the head 106 and welded to the head so that it projects centrally into the inlet pipe 94 is a reflux inlet pipe 107. In Figs. 6 and 9 openings 110 are shown provided in the inlet pipe 94 along its top side and openings 111 are provided in the pipe 107 to one side of the top side thereof so as to be out of registry with the holes 110. The purpose of providing the holes 110 and the holes 111 out of alignment with each other will be described later.

The condensing pan 75 with the inlet and outlet condensate pipes 94 and 95 and the reflux inlet pipe 107 comprises a condensing pan assembly 112.

Identical in structure and manner of mounting with the assembly 112, and mounted one above the other in the shell 62 between the lower end thereof and the medial vestibule chamber 70 are condensing pan assemblies 115 and 116.

As indicated by dotted lines in Fig. 6, a pipe joint flange 120 is screwed upon each of the condensate discharge pipes 94 of the pan assemblies 115 and 116 and as shown in Fig. 2 the flanges 120 have gas trap elbows 121 and 122 joined thereto by end flanges 123 thereof.

A pipe 125 having suitable connecting end flanges connects adjustable weir housing 100 with the elbow 121 which communicates with the condensate inlet pipe 94 of the pan assembly 115. The condensate outlet pipe 95 of the pan assembly 115 has an adjustable weir 126 which is connected by a pipe 127 to the elbow 122 which communicates with the condensate inlet pipe 94 of the pan assembly 116. The outlet pipe 95 of the pan assembly 116 has a weir valve 128.

The re-boiler section 61 has a shell 130 of identical cross section with the shell 62 and is disposed beneath the shell 62 in alignment and in contact with it. A flange 131 provided at the upper end of the shell 130 is suitably secured to the flange 66 to form a gas-tight joint between the shells 130 and 62. A flange 132 provided at the lower end of the shell 130 is secured to a base plate 133. A

re-boiler floor plate 135 is welded into the shell 130 to form a boiling chamber 136.

As clearly shown in Figs. 4, 10 and 11, parallel hollow baffle walls 137 are formed upon the floor 135 alternately spaced from and joined to the opposite ends 138 and 139 of the shell 130 so as to divide the chamber 136 into a circuitous passageway beginning and ending at the corners 140 and 141 respectively of the shell 130.

Opening into the shell 130 at its corner 140, as shown in Fig. 10, is an inlet pipe 142 and opening from the shell 130 at its corner 141 is an outlet pipe 145.

15 The inlet pipe 142 is connected through a gas trap elbow 146 and a standard 90° elbow 147 is connected to the adjustable weir 128.

20 Tubes 149 pass through holes in the ends 138 and 139, as shown in Figs. 11 and 12, so as to form a dry heating element 150 in each of the aisles 151 formed by the baffle walls 137. These tubes 149 are rolled into a gas-tight fit in the shell ends 138 and 139, and project outwardly a short distance therefrom, where they 25 pass into and are rolled to fit tightly holes provided in inlet and outlet header boxes 155 and 156. These header boxes 155 and 156 have face plates 157 secured on the outer ends thereof which may be removed to provide access to the tubes 149 for cleaning. An inlet pipe 160 is provided in the header box 155 and an outlet pipe 161 is provided in the box 156.

30 A collar 165, as shown in Fig. 12, is provided in the shell end 138 opposite each of the aisles 151 and just above the floor 135. A perforated steam outlet pipe 166 passes through the collar 165 and extends into the chamber 136 almost to the opposite end wall 139. The inner end of each pipe has a cap 35 167 and the outer end has a steam valve 168 which connects through a nipple 169 to a steam manifold 170.

35 The fractionating units 52, 53, 54, 55, 56 and 57 being identical in structure, a detailed 40 description of the unit 52 will suffice for all of these units which are stacked consecutively upon each other as shown in Fig. 1, above the unit 40.

45 The fractionating unit 52, as shown in Fig. 4, comprises a condensing section 180 and a re-boiler section 181. The re-boiler section 181 is identical to the re-boiler section 61 with the exception that in place of the baffle walls 137, baffle walls 185 are provided which not 50 only perform the functions of the walls 137 but are open at the top and provide passageways 186 communicating between the space 187 below the floor 135 and the space 188 above the re-boiling chamber 136.

55 The condensing section 180 has a shell 190 which is of the same size as the shell 62 of the vestibule condensing section 60 of the lowermost fractionating unit 40. The shell 190 has six condensing pan assemblies 191, 192, 193, 194, 195 and 196, each identical with

the pan assembly 112 and mounted, as shown in Fig. 4, in the same manner, one below the other.

As shown in Figs. 3 and 4, the pan assemblies 191 to 196 have outlet overflow adjustable weirs 201 to 206 respectively. The pan assemblies 192 to 196 have inlet gas trap elbows 212 to 216 respectively.

70 A pipe 222 connects the overflow weir 201 to the inlet elbow 212. Similarly, the overflow weirs 202 to 205 are connected by pipes 223 to 226 respectively to inlet elbows 213 to 216 respectively.

75 The condensate inlet pipe 94 of the upper pan assembly 191 has a cap 230 similar to the cap 97 on the pipe 94 of the pan assembly 112.

80 The weir 206 is connected to the flanged inlet pipe 142 of the re-boiler 181 by a gas trap elbow 231 and a right elbow 232.

85 The lower flange 132 of the re-boiler section 181 is secured to the upper flange 65 of the condensing section 60 to form a gas-tight joint between these sections. Likewise, the upper flange 131 of the re-boiler section 181 is secured to the lower flange 66 of the condensing section 180 to form a gas-tight joint 90 between these sections.

95 In a similar manner all pairs of adjacent ends of the condensing and re-boiler sections of the fractionating units stacked upon each other above the unit 52 are joined together by flanges to form gas-tight joints therebetween.

100 Resting upon the upper end of the top fractionating unit 57 is a tower cap 200. A flange 207 formed upon the cap 200 is secured to the upper flange 65 of the unit 57 and forms a gas-tight union between the cap 200 and the unit 57.

105 Referring again to Fig. 1, a vapor line 208 is provided to lead from the top of the tower cap 200 to a gasoline condenser 209. A condensate rundown line 209^a leads from the bottom of the condenser 209 to a storage tank 210.

110 A boiler 211 generates steam which is conducted through a steam pipe 217 to each of the re-boiler steam manifolds 170. Likewise, a steam line 218 leads from the pipe 217 to the vaporizer 31 which, as diagrammatically illustrated, is the novel vaporizer shown, described and claimed in our United States Letters Patent, issued October 11, 1927, No. 1,644,937, to which reference may be had if further information regarding it is desired.

115 It is desirable that the temperature of the re-boilers be controlled over quite a large range. Means are therefore provided for supplying a heat exchanging medium to the header boxes 155 of the various fractionating unit re-boilers and running the medium away from the header boxes 156, thus causing a flow of the medium through the tubes 149. The intake of a residuum pump 220 is controlled by valves 221 and 221^a which communicate 120

125 130

respectively with the hot residuum line 32 and with a line 223^a leading to the crude oil storage tank 11. The adjustment of the valves 221 and 221^a determines whether the heat exchanging medium drawn into the pump 220 will be hot residuum, cool crude oil or a mixture of residuum and crude. From the pump 220 an outlet pipe 225^a communicates with a stand pipe generally designated as 226^a.

As shown in Fig. 3, this pipe 226^a is built-up. Starting at the bottom, the parts as far as fragmentarily shown, comprise a T fitting 230^a, a shut-off valve 231^a, a pipe 232^a, a four-way fitting 233, a valve 234, a pipe 235, a four-way fitting 236 and a valve 237.

The T fitting 230^a communicates through a pipe 240, a regulating valve 241 and an elbow 242 with the inlet residuum header box 155 of the lowermost re-boiler 61. The four-way fitting 233 communicates on the right hand side through a pipe 245, an elbow 246 and a valve 247 with the inlet header box 248 of the re-boiler 181. The fitting 233 communicates on the left hand side through a pipe 250, an elbow 251, a pipe 252, an elbow 253, a pipe 254, a valve 255, and a T fitting 256 with the residuum outlet header box 156. The four-way fitting 236 communicates on the right hand side through a pipe 260, an elbow 261, and a valve 262 with the inlet header box 263 of the re-boiler 264 of the fractionating unit 53.

The fitting 236 communicates on the left hand side through a pipe 270, an elbow 271, a pipe 272, an elbow 273, a pipe 274, a valve 275 and a T fitting 276 with the residuum outlet header box 277 of the re-boiler section 181.

A built-up residuum return line 280 has a pipe 281 which leads to a residuum storage tank (not shown) and upon the upper end of which is assembled in the following order, a T fitting 282, a pipe 283, a T fitting 284 and a pipe 285 which is shown in Figs. 2 and 3 as broken off. In the portion of the fractionating tower which is shown as broken away in Fig. 3 the pipe 285 has a T fitting secured thereto and above this are joined successively a pipe and a T fitting for each of the fractionating units 54, 55, 56 and 57, the uppermost of these being a pipe 290 and a T fitting 291, the upper end of which is sealed by a plate 292.

The T fitting 282 connects through a valve 295 and an elbow 296 with the T fitting 256. The T fitting 284 connects through a valve 297 and an elbow 298 with the T fitting 276. The T fitting 291 connects through a valve 299 and an elbow 300 with the outlet residuum header box 310 of the re-boiler section 311 of the uppermost fractionating unit 57.

As shown in Fig. 4, the outlet pipe 145 of the re-boiler section 181 connects to the lower end of a vertical pipe 320 which rises to a level slightly lower than the top of the baffle

walls 185, where it connects to a horizontal pipe 321 which in turn connects to a vertical condensate run-down pipe 325. In the same manner condensate run-down lines 324, 326, 327, 328, 329 and 330 are connected respectively to the re-boiler sections of the other fractionating units 40, 53, 54, 55, 56 and 57.

As shown in Fig. 1, the run-down lines 324, 325, 326, 327, 328, 329 and 330 pass through the primary heat exchangers 13 and lead respectively to condensate storage tanks 334, 335, 336, 337, 338, 339 and 340.

As illustrated in section in Fig. 15, a gas pocket preventer 344 in the form of a small cylindrical condenser 345 is disposed vertically above the horizontal pipe 321 and has a neck pipe 346 which connects the two.

The condenser is of the standard cylindrical form and has upper and lower floors 348 and 349 forming upper and lower condensing chambers 350 and 351 and a medial water chamber 352 through which pipes 353 pass, having their ends rolled into suitable holes in the floors 348 and 349 communicating between chambers 350 and 351. Inlet and outlet water pipes 355 and 356 connect with the water chamber 352 and are provided with water circulating means (not shown) which maintain the pipes 353 and the chambers 350 and 351 at a relatively low temperature.

A T fitting 357 communicates through a nipple 358 with the chamber 350 and through nipples 360 and 361 with a check valve 362 and a hand valve 363 respectively. The check valve 362 permits atmosphere to flow into the chamber 350, but prevents an outward flow therefrom. The hand valve 363 may be opened to allow gas in the chamber 350 to escape to the atmosphere.

As shown in Figs 1, 2, 5 and 6, each of the reflux inlet pipes 107 has a flow-regulating valve 370 which connects to a nipple 371 projecting from a reflux manifold 372. Each of the fractionating units has a separate manifold 372 which is provided (as that shown in Fig. 1 for the unit 57) with a supply pipe 375 which leads to a pressure pump 376 which has an inlet manifold 377 through which it may draw condensate from any of the tanks 210 or 334 to 340 inclusive, and supply this for use as a reflux to a particular manifold 372.

The centrifuge 36, as shown in Figs. 13 and 14, has a shell 380 of inverted conical form and has a tangential vapor inlet 381 provided at the upper end thereof and a vertical central vapor outlet pipe 383 projecting downwardly through the center thereof to within a short distance of the bottom, from which the liquid drain pipe 37 leads through a gas trap 385 back to the vaporizer 31. In the present use of the centrifuge 36 a separation of entrained liquid particles from the vapor leaving the vaporizer 31 is effected by the rapid rotation of the vapors in the centrifuge 36. The separated liquid drains back

into the vaporizer 31 through the pipe 37 and the gas trap 385.

The method of operation is as follows: As previously stated the refining process carried on by the apparatus illustrated in Fig. 1 is a continuous process. When the process is started, vapor is supplied as described through the vapor line 38 to the lowermost fractionating unit 40 of the fractionating tower 41. The reflux valves 370 are opened, each of the pumps 376 is connected through its manifold 377 with one of the condensate storage tanks, and the pumps 376 are started. This supplies the desired grade of condensate as a reflux to each of the reflux manifolds 372, from which it passes through the valves 370 into the reflux inlet pipes 107 and, passing through the holes 111, fills the condensate inlet pipes 94, overflows through the holes 20 110 and fills each condensing pan in the whole tower to a level predetermined by the setting of the rotors 101 of each of the level controlling weir valves. The maximum level thus attainable in any of the condensing pans is 25 slightly below the top of the riser opening walls 78 so that under no circumstances may liquid in a condensing pan overflow through the riser openings 77. The minimum level attainable by control of the weir valve is located slightly above the shelf flange 93. Thus, after the operation of the tower is once started and the condensing pans filled with reflux to their minimum level, vapor passing from below any given pan to the space above it must pass up through the riser openings 77 into the cavity 84 of the caps 80, downwardly between the riser walls 78 and the cap walls 82 and 83, out through the notches 91 underneath the shelf 93 and upwardly at the shelf's outer edge through a layer of liquid reflux.

In entering the fractionating tower 41, the vapor mixture passes into the chamber 70 of the fractionating unit 40 and flows upwardly therefrom through the holes 73 in the distributor plate 72 and is uniformly distributed over the space 390 above the plate 72. From the space 390 the vapor passes up through the condensing pan 75, as above described. A few of the least volatile constituent vapors are thereby condensed from the mixture due to a slight drop in temperature in its passage through the reflux in the pan 75. As this condensation continues in the pan 75 the condensate accumulates and raises the level of liquid in the pan so that it overflows through the weir valve 100, passes down the pipe 125 through the gas trap elbow 121 and into the inlet pipe 94 of the condensing pan 115. The level of liquid thus being raised in the pan 115, an overflow therefrom passes through the weir 126 through the pipe 127 and the gas trap elbow 122 into the inlet pipe 94 of the condensing pan 116. The level of liquid being thus raised in the pan 116, 60 an overflow therefrom passes through the

weir valve 128, through the elbows 147 and 146 and the inlet 142 into the re-boiler 61. Here the mixture of reflux and condensate accumulates until the level is reached, where the liquid will flow from the vertical pipe 320 70 along the horizontal pipe 321 and down the condensate run-down pipe 324 to the storage tank 334.

The portion of the vapor mixture which is not condensed in the pan 75 passes from 75 the space 187 thereabove, up through openings 186, in the baffle walls 185 in the re-boiler 181, to the space 188, and from there it passes up successively through the condensing pans 196 to 191 inclusive in the condens- 80 ing section 180. In each of these pans a portion of the less volatile of the remaining vapors in the mixture is condensed by being slightly cooled in passing through the liquid contained in the pan. As the level of liquid rises in each pan due to an accumulation of the condensate, the mixture of reflux and condensate overflows therefrom. This overflow from the pan 191 passes through the weir 201, the pipe 222 and the elbow 212 into 90 the inlet pipe 94 of the pan 192. Traversing the length of the pan 192 and thoroughly mixing with the liquid therein, this overflow from the pan 191 passes off with the overflow from the pan 192. In the same manner 95 the overflow from the pan 192 passes down to the pan 193, and the overflow from the pan 193 passes to the pan 194, and so on, until the accumulated overflow from all the condensing pans 191 to 196 inclusive is conveyed 100 through the weir 206, the elbows 232 and 231, and the inlet 142, into the re-boiler 181. The liquid collects in the re-boiler 181 until it reaches the level from which it overflows down the run-down pipe 325 to the storage 105 tank 335.

The gas pocket preventer 344 is provided to condense any vapor which may form in any of the horizontal pipes 321. If vapor were allowed to collect and form a pocket in 110 a pipe 321, this would stop the passage of condensate into the run-down line connected thereto and cause the condensate in the re-boiler, from which it is the outlet, to overflow into the condensing section below. The check valves 362 are provided to permit access of the atmosphere to each pipe 321 to prevent sufficient vacuum being formed therein to start a siphoning action from any re-boiler down its run-down line. The hand valves 115 363 permit manual release of any gaseous hydrocarbons collecting in any pipe 321 of too light a nature to be condensed by the condenser 345. As this condition very rarely occurs, no great inconvenience is occasioned 120 by the necessity of manually relieving it.

The portion of the vapor mixture which passes uncondensed through the pan 191 into the space 395 thereabove continues on up successively through the higher fractionating 130

units 53, 54, 55, 56 and 57. In each of these units the temperature is a certain number of degrees lower than in the next unit below. Thus, vapors of certain liquefying temperatures that will pass through the lower fractionating units, due to the higher temperatures, will upon reaching the first fractionating unit having a temperature below their liquefying temperature condense and separate out from the vapor mixture as a condensate.

As these condensates collect in the initial charge of reflux in the condensing pans, the flow of reflux into the various condensing pans is cut down by the valves 370 so that the amount of reflux introduced into each pan during the normal operation of the tower 41 is very small in proportion to the condensate formed in that pan. The effect of the introduction of reflux is well known in the art and varies with the gravity and boiling point of the reflux. Special attention may be directed, however, to our novel means of thoroughly mixing the reflux in each pan condensate inlet pipe 94 with the condensate flowing thereinto from the higher pans in that fractionating unit. This equal distribution is highly important to the uniform treatment of all portions of the condensate and reflux mixture as it flows through each pan and uniformity in the product depends largely upon this uniformity of action upon all parts of the condensate flowing through each of the pans.

The general purpose of the condensing sections, therefore, is to fractionally condense in a succession of cooling stages the vapors of successively lower liquefying temperatures contained in the vapor mixture entering the tower. This condensation successively of certain groups of vapors from the vapor mixture, each of which groups has lower liquefying temperatures than the other vapors remaining in the vapor mixture, is not ideally attainable by control of the temperature of the pans of condensate alone. This is due to absorption by the condensate of some of the vapors which normally liquefy only at a lower temperature than that of the condensate. The vapors thus absorbed in a given condensing section which are lighter than desired in the product from that section must be driven off. This is accomplished by heating the condensate to boiling temperature in the re-boiler section immediately below each condensing section by the circulation of residuum through the pipes 149. Driven off by the boiling of the condensate, these lighter vapors again pass up through the condensing section in which they were first absorbed, and while a small part of them is re-absorbed a large proportion escapes on up to the next higher fractionating unit and continues on up in this manner until it is condensed in the unit in the product of which it belongs. The

bulk of the condensate which passes into each re-boiler consists of the product desired to be fractionally condensed in that unit. Some of this product is vaporized in the boiling and driven off with the lighter absorbed vapors, but this product is all re-condensed in the condensing section above and returned to the re-boiler. The condensate enters the re-boiler at the corner 140, as shown in Fig. 10, and flows serially through the five aisles 151 into which the re-boiler chamber 136 is divided by the baffle walls 137, and is exposed to the dry heat supplied by the heat exchange units 150 disposed in each of the aisles 151. Therefore, when the condensate reaches the corner 141 and passes out the pipe 145 to its respective run-down line, all the hydrocarbons of lower boiling point than those desired are driven off as vapors and a product of exactly the desired initial and end boiling points is secured.

The temperatures of the fractionating units progressively decrease from the bottom to the top of the tower. This reduction in temperature is controlled in the condensing pans by the temperature and grade of reflux admitted and by the depth of liquid maintained in each pan. In the re-boilers the temperature is controlled by the amount of hot residuum allowed to flow through the heat exchange pipes 149 and by the introduction of a greater or less amount of live steam through the perforated pipes 166, shown in Figs. 10, 11 and 12.

The piping described as connecting the supply residuum pipe 226^a and the return residuum pipe 280 with the re-boilers is arranged to provide for passing the residuum from the pipe 226^a through the re-boilers either in parallel or in series to the return pipe 280. This is a great advantage in that certain crudes may be suitably refined in our fractionating tower when the temperatures of the re-boilers decrease progressively from the bottom re-boiler to the top re-boiler, due to the progressive cooling of residuum passed serially through the re-boilers one after the other, from the bottom unit on up to the top unit where it is discharged to the return line.

As shown in Fig. 3, the series flow of residuum is accomplished by closing the valves 231^a, 234, 237 and so forth on up to the topmost valve (not shown) of the residuum supply pipe 226^a, which topmost valve is always kept closed during normal operation. Also the valves 295, 297 and all similar valves communicating between the residuum return line 280 and the re-boilers; excepting the topmost valve 299, are closed. The valves 241, 247, 262, 255, 275 and all similar valves, on the fractionating units which are broken away, are opened.

The residuum valve 221 is then opened and the pump 220 started. Residuum flows through the pipe 225^a to the T fitting 230^a

and through the pipe 240, the valve 241 and the elbow 242 to the intake header box 155 of the re-boiler 61. The residuum flows through the tubes 149 of the re-boiler 61 to 5 the outlet header 156, from which it passes through the T fitting 256, the valve 255, the pipe 254, the elbow 253, the pipe 252, the elbow 251, the pipe 250, the fitting 233, the pipe 245, the elbow 246 and the valve 247 into 10 the inlet header 248 of the re-boiler 181. The residuum flows through the tubes 149 of the re-boiler 181 to the outlet header 249 and thence through the T fitting 276, the valve 275, the pipe 274, the elbow 273, the pipe 272, the elbow 271, the pipe 270, the fitting 236, the pipe 260, the elbow 261 and the valve 262 to the header box 263. From here the residuum passes through the re-boiler 264 and from there serially through the upper 15 20 re-boilers in the same manner as it has just been described as passing through the re-boilers 61, 181 and 264. After flowing through the re-boiler 311 of the uppermost fractionating unit 57, the residuum passes 25 into the outlet header box 310 and is conveyed from this through the fitting 300, and the valve 299 to the top fitting 291 of the residuum return line 280. From here the cooled residuum passes through the line 280 30 to the pipe 281, which empties into the residuum storage pipe 34.

When it is possible to route the residuum thus in series through the re-boilers from the bottom to the top of the tower, a maximum efficiency in the extraction of the heat 35 from the hot residuum is accomplished. This is a great advantage in that only a small quantity of residuum need be diverted from the secondary crude oil heat exchangers 15 40 for heating the re-boilers in the tower. However, the temperature of each successive re-boiler through which the residuum flows in series is dependent upon the temperature to which the residuum has been reduced in the 45 re-boilers previously passed through.

When the re-boiler temperatures thus attained are not suitable for the proper fractionating of a given vapor mixture, the parallel routing of the residuum through the 50 re-boilers referred to above is set up. This is accomplished by opening the valves 231^a, 234 and 237 and all other of the residuum supply line valves excepting the topmost valve which remains closed as above noted. 55 The valves 255, 275 and all similar valves on the portion of the residuum piping broken away are closed. The valves 295, 297 and all similar valves are opened, excepting the topmost of these valves 299 which merely re- 60 mains open.

The hot residuum then passes up the supply pipe 226^a and out through the pipes 240, 245, 260 and similar pipes for the re-boilers, not shown in detail. These pipes connect re- 65 spectively through the valves 241, 247, 262, et

cetera, with the residuum intake headers 155, 248, 263, et cetera. From the header 155 the residuum flows through the re-boiler 61 and out from the outlet header 156, through the fittings 256 and 296, and the valve 295, to the 70 residuum return line 280. From the header 248 residuum passes through the re-boiler 181, the header 249, the fittings 276 and 298, and the valve 297, to the return residuum line 280. In the same manner residuum passes 75 from the supply line 226^a in parallel through all the re-boilers to the return line 280.

In the parallel routing of residuum through the re-boilers the temperature of each re-boiler is controlled by the amount of residuum allowed to pass through the re-boiler. Means for this control are provided in the valves 241, 247, 262, et cetera.

In case a large volume of hot residuum were desired to be passed through two or more of the lower re-boilers, these might be connected together in series and the re-boilers thereabove in parallel.

It will thus be seen that we have produced a single fractionating tower by which a mixture of hydrocarbon vapors may be fractionally condensed into several commercial products, each comprising a certain adjacent group of the hydrocarbons contained in the vapor mixture. This result can only be accomplished by our exact temperature control means.

Another very important result of our accomplishing the complete fractionating process in a single tower, combined with our novel 100 residuum circuit which utilizes the heat of the hot residuum to almost 100 per cent efficiency, is the marked economy of operating a refining apparatus in which our fractionating tower is used. In our operation of such a plant, the 105 fuel consumed has been as low as 1.75 per cent of the crude treated and has averaged under 2 per cent over a period of two months operation handling various grades of crude oil. The very best performance previously recorded 110 by the largest and most progressive oil companies in refinery practice is a consumption of fuel equal to 2.25 per cent of the oil treated.

In addition to this revolutionary economy 115 of operation of our fractionating tower is the accuracy of control of the dephlegmating action in the various fractionating units which permits cuts to be made from the vapor mixture, the initial boiling point of each 120 of which is higher than the end point for the next lighter cut. This control eliminates the cost of redistilling cuts having wrong initial or end boiling points which, as well known, has been heretofore an almost common practice in the petroleum refining industry.

What we claim is:

1. In a dephlegmator the combination of: walls forming a vertical closed chamber;

means for passing a vapor mixture into the bottom of said chamber; means for conducting a vapor mixture from the top of said chamber; floor plates secured to said walls to form a series of dephlegmating pans disposed one over the other; walls forming risers in said floor plates; caps disposed over the upper ends of said risers so that the mouths thereof are disposed on a level between the top of said riser and the floor in which it is formed; means for conducting condensate from above a certain level in each of said pans, excepting the lowermost, into the pan therebelow; means for regulating the height of said levels from which condensate is drawn; and means for drawing condensate from said lowermost pan.

2. In a fractionating tower, the combination of: a plurality of units placed one above the other providing a series of fractionating stages, each of said units comprising a condensing section and a re-boiling section disposed immediately under said condensing section, each of said condensing sections comprising a series of pans having walled riser openings therein and caps placed over said riser openings and adapted to deflect vapors rising through said openings downwardly into said pans, and each of said re-boiling sections comprising an open boiler having walled riser openings therein; means for conducting condensate from the lowermost pan of each condensing section to its re-boilers; means for conducting condensate from each of the other pans to the one immediately beneath it; and means for determining the level above which condensate is drawn from each of the pans.

3. In a fractionating tower, the combination of: a plurality of units placed one above the other providing a series of fractionating stages, each of said units comprising a condensing section and a re-boiling section disposed immediately under said condensing section, each of said condensing sections comprising a series of pans having walled riser openings therein and caps placed over said riser openings and adapted to deflect vapors rising through said openings downwardly into said pans, and each of said re-boiling sections comprising an open boiler having walled riser openings therein; a heat exchange element in each re-boiler section; a supply pipe for supplying hot residuum to said heat exchange elements; a return pipe; and means connecting said heat exchange elements with said supply and return pipes whereby the residuum may be run from the supply pipe through said heat exchange elements in parallel relation to the return pipe or from the supply pipe through said heat exchange elements in series to the return pipe.

4. A combination as set forth in claim 3 in which each re-boiler section has a run-down line; an inverted U-shaped pipe connecting

the upper end of each run-down line with the lower portion of its respective re-boiler; and means for condensing any vapor pocket which may form in said U-shaped pipe.

5. A combination as set forth in claim 2 in which means are provided for supplying steam directly to the condensate in each re-boiler section.

6. A combination as defined in claim 2 to which is added: means for introducing a reflux liquid into the condensate and thoroughly mixing the reflux with said condensate where the condensate is discharged in said pans.

7. In a fractionating tower, the combination of: a plurality of units placed one above the other providing a series of fractionating stages, each of said units comprising a condensing section and a re-boiling section disposed immediately under said condensing section, each of said condensing sections comprising a series of pans having walled riser openings therein and caps disposed over said riser openings adapted to deflect vapors rising through said openings downwardly into said pans, each of said re-boiling sections comprising an open boiler having walled riser openings therein, and a run-down line; a pipe connecting the upper end of each run-down line with the lower portion of its respective re-boiler; a heat exchange element in each re-boiler section; a supply pipe for supplying hot residuum to said heat exchange elements; a return pipe; a check valve provided to communicate between said first mentioned pipe and the atmosphere; and means connecting said heat exchange elements with said supply and return pipes and adapted to run the residuum through said heat exchange elements in parallel relation to the return pipe or through said heat exchange elements in series to the return pipe.

8. In a fractionating tower, the combination of: a plurality of units placed one above the other providing series of fractionating stages, each of said units comprising a condensing section and a re-boiling section disposed immediately under said condensing section, each of said condensing sections comprising a series of pans having walled riser openings and caps disposed over said openings adapted to deflect vapors rising through said openings downwardly into said pans, each of said re-boiling sections comprising an open boiler having walled riser openings therein; a heat exchange element in each re-boiler section; a supply pipe for supplying hot residuum to said heat exchange elements; a return pipe; and means for running the residuum from the supply pipe through said heat exchange elements in parallel relation to the return pipe or through said heat exchange elements in series to the return pipe.

9. A combination as set forth in claim 8 including: a run-down line for each re-boiler

section; a pipe connecting the upper end of each run-down line with the lower portion of its respective boiler; and means for condensing vapor which may form in a pocket

5 in said pipe connecting the run-down line with its respective re-boiler.

10. A combination as set forth in claim 8 in which each re-boiler section has a run-down line and an inverted U-shaped pipe

10. connecting each run-down line with its respective re-boiler.

11. A combination as set forth in claim 7 in which said first mentioned pipe is U-shaped.

15. 12. A combination as set forth in claim 7 in which means is provided for condensing vapor which may form in a pocket in said first mentioned pipe.

In testimony whereof, we have hereunto

20 set our hands at Los Angeles, California, this 24th day of December, 1925.
